UNITED STATES PATENT OFFICE.

ROY DODSON, OF DALLAS, TEXAS.

DESIGN FOR A HAME ATTACHMENT.

SPECIFICATION forming part of Design No. 34,069, dated February 12, 1901.

Application filed January 14, 1901. Serial No. 43,289. Term of patent 14 years.

To all whom it may concern:

Be it known that I, ROY DODSON, a citizen of the United States, residing at Dallas, in the county of Dallas and State of Texas, have invented and produced a certain new and original Design for Hame Attachments; and I do declare the following to be a full, clear, and exact description of the invention, such as will enable others skilled in the art to which it appertains to make and use the same.

The invention relates to a new and original design for hame attachments; and it consists of a design of the configuration shown in the accompanying drawings, in which I have illustrated the invention in perspective.

The leading feature of the design comprises

a body 1, having laterally-projecting arms 2, terminating in circular perforated heads 3. Projecting from the opposite side of the body portion are two lugs 4, provided with aligned perforations 5.

What I claim is—

The design for a hame attachment as herein shown and described.

In testimony whereof I have hereunto set my hand in the presence of two subscribing witnesses.

ROY DODSON.
